BRAIDING MACHINE

Edward A. Davis, Akron, Ohio, assignor to The
B. F. Goodrich Company, New York, N. Y., a
corporation of New York

Application July 15, 1942, Serial No. 450,947

6 Claims. (Cl. 87—21)

This invention relates to multiple strand braiding, and more especially to the tensioning of the strands.

It has been found desirable to braid bands each consisting of a number of parallel strands of wires or cords rather than single strands, but in prior attempts difficulties have been encountered especially in that uniform tension on the bobbins has not been effectively provided, resulting in over-tensioning of some strands of the wires or cords with consequent stretching or breaking of these strands or in failing to provide sufficient tension in certain strands resulting in looseness of these strands in the braid.

The present invention aims to overcome the foregoing and other difficulties.

The principal objects of the invention are to provide for improved manipulation of bands having multiple strands, to provide uniform tension of the strands, to prevent over-tensioning and breaking of the strands, to provide automatic adjustment of individual strand tension, to provide concurrent adjustment of a group of strands, and to provide reliability of operation and economy of materials.

These and other objects will appear from the following description and the accompanying drawing.

Of the drawing,

Fig. 1 is a plan view of a portion of a circular 30 braiding machine constructed in accordance with and embodying the invention.

Fig. 2 is a front elevation of one of the shuttles, the raceway being indicated by broken lines.

Fig. 3 is a side elevation thereof, looking from the left of Fig. 2.

Fig. 4 is a sectional view thereof, taken on line 4—4 of Fig. 3.

Fig. 5 is an elevation of a modification of the shuttle of the invention.

Fig. 6 is a sectional view thereof, taken on line 6—6 of Fig. 5.

In the embodiments of the invention illustrated in the drawing, a plurality of bobbins are arranged on a single spindle of a shuttle for group tensioning and are tensioned uniformly and simultaneously by tension means thereon. Provision is made for adjusting the tensions of the individual strands automatically.

The numeral 10 designates the raceway of a braiding machine and 12, 13 are the intersecting grooves of generally cycloidal shape along which the carriers 14 are driven by gearing (not shown). Strands 15 drawn from the carriers are braided about the tubular core 16 at the center

of the raceway, the strands being guided over a ring 10a which directs them to the braiding position without great difference in the lengths extending from any position of the carrier to the 5 braiding position, due to location of the ring at a mean position.

The carrier in one form of the invention is shown at 14 in Figs. 2 to 4 and has a spindle 17 for retaining a plurality of bobbins 18, 19, 20, 21 in side-by-side relation. The arrangement is such that each bobbin can turn freely with respect to the spindle. The free end of the spindle has a cross-slot 22 for slidably receiving a key 23 whereby the bobbins may be retained against removal. The spindle slot is open to the end of the spindle. The key has a slot 24 therein terminating near one end of the key which is rounded. A cross pin 25 extends through the slotted portions of the key and the spindle. The arrangement is such that by sliding the key radially until its rounded end is adjacent the pin 25, the key may be rotated to a position where it clears the holes in the bobbins for bobbin removal. Discs 45, 46, 47 of friction material, such as 25 brake lining are loosely mounted between the bobbins so that each bobbin acts as a brake against adjoining ones and induces rotation thereof.

For additionally tensioning the bobbins, a standard 30 is fixed to the carrier adjacent the bobbins and has a plurality of parallel spaced-apart webs 31, 32, 33, 34, 35 having apertures therethrough in alignment to receive a shaft 36 arranged parallel to the axis of the bobbins. Between each pair of webs is a bell crank, for example 37, on one arm of which is an arcuate brake shoe 38 adapted to frictionally engage the rim of an adjacent bobbin. A torsion coil spring 39 encompasses the shaft 36 and has one end 40 thereof fixed to the bell crank 37 and the other end thereof fixed to the adjacent web 35. The arrangement is such that the spring urges the brake shoe radially against the bobbin. A second bell crank lever 40 is pivoted on a pin 41 arranged at right angles to shaft 36 and has an arm 40a having an eye 42 for guiding a bight of the strand from the bobbin. The other arm 40b of the bell crank 40 extends substantially axially of the bobbin and bears against an arm of the brake shoe bell crank 37 as at 43. A guide eye 44 is fixed to the free end of standard 30. The strand 15 extends from bobbin 21 through eye 42 and outwardly with other strands through eye 44. The arrangement is such that if the tension in strand 15 becomes excessive arm 40 is

drawn toward eye 44 against the tension of spring 39 the brake shoe 38 is momentarily lifted away from the bobbin, relieving the excessive tension. At the same time the bobbin is frictionally held against overrun by the adjacent friction disc.

Each bobbin has a corresponding brake and the strands from each of the bobbins are led through the eye 44, the arms 48 of the various bell cranks being offset in succession as seen in Fig. 4 so that the reaches of the strands clear each other. The strands from each carrier are laid in parallel in the braid and any excessive tension of an individual strand is automatically adjusted to equalize tension of the group of strands.

In the embodiment of the invention illustrated in Figs. 5 and 6 a carrier 50 has a spindle 51 fixed thereto as by a pin 75. This spindle is round in cross section, a hollow quill 70 is rotatably mounted thereon and is flattened on two opposite sides as at 70a, 70b. It has an enlarged head at its free end and is threaded near its other end as at 70c to engage a threaded nut 62. A series of discs 53, 54, 55, 56, 57, 58, 59 are slidably but non-rotatably fitted on the quill 70. Discs 54, 55, 56, 57 and 58 are of friction material, such as brake lining to induce or retard movement of one bobbin with relation to another. Between pairs of adjacent friction discs bobbins 60, 61, 62, 63 are rotatably mounted about the quill 70.

A cross slot 84 is formed in the free end of spindle 51 and receives a key 64a for retaining the quill against axial movement. A hollow standard 65 is mounted on the carrier 50 and extends parallel to spindle 51. It carries a guide arm 66 fixed to its upper end. An arm 67 is slidably mounted on standard 65 and is retained against rotation by a key 68 on the standard engaging a keyway in the arm 67. Disc 59 is formed with ratchet teeth 59a on its upper face, each having an axial face and an inclined face. Arm 67 is of cross-section complementary to one of the slots between the teeth. A compression coil spring 71 encompasses the standard 65 between the guide arm 66 and the slidable arm 67. A second compression coil spring 72 encompasses the quill 70 between the nut 62 and the lower disc 53. A guide bar 73 is fixed to the carrier parallel to standard 65 and has a plurality of guide eyes 73a, 73b, 73c, 73d for individually guiding strands from the bobbins 60, 61, 62, 63, respectively. The strands are then grouped and pass collectively through the single guide 65a on the outboard end of standard 65. The hollow standard 65 has elongated axial slots 65b in opposite sides thereof. A collar 75 is slidably mounted on the standard and has a guide eye 76 thereon. A pin 77 is fixed to the collar and extends through the standard by way of the slots 65b. A compression coil spring 78 is mounted in the bore of the hollow standard with one end resting against a cross pin 79 and the other end bearing against cross pin 77. The grouped strands from the guide eye 65a are looped through the guide eye 76 on the sliding collar 75 and then pass through a guide eye 80 on arm 66 from which they pass to the braiding position. The arrangement is such that coil spring 78 tensions all the strands of the group and under increased resistance tending to over-tension the strands the collar 75 can slide along the standard comprising the coil spring 78.

The bobbins are wound in such a direction that

in withdrawing the strands the disc 59 is urged in a direction to press the inclined faces of its teeth 59a toward the inclined face of arm 67 or in a clockwise direction in Fig. 6. The arrangement is such that normally the ratchet arm 67

holds the disc 59 and consequently the quill 70 and brake discs 53, 54, 55, 56, 57 and 58 against rotation but each of the bobbins 60, 61, 62 and 63 may turn under the pull of its strand against the frictional resistance of the brake discs. When the pull on any strand is too great, for example, of such magnitude as to endanger the strand, the pressure of springs 71, 72 is overcome and the inclined surface of the ratchet tooth 59a against arm 67 lifts arm 67 permitting quill 70 to rotate a notch and relieving the strain. Arm 67 then engages the next tooth of the disc 59. Nut 62 may be adjusted to regulate the spring tension on the ratchet.

20 In both the illustrated embodiments of the invention, a plurality of strands are supplied from a single carrier and provision is made for release of tension when such tension becomes excessive on any one of the strands. In the form of the invention of Figs. 2 to 4 the tension on the over-tensioned strand is reduced automatically by tightening of the bight of the strand at the eye 42, while in the embodiment of Figs. 5 and 6 such over-tensioning of any one of the strands automatically reduces tension of all the strands carried by the same carrier first by movement of the collar 75 against coil spring 78 and later if excessive movement takes place, by lifting of arm 76 releasing ratchet disc 59 one tooth, the coil spring 78 preventing slack of the strands. Such release is only momentary as the ratchet arm 67 engages the next tooth immediately.

Variations may be made without departing from the invention as it is defined by the following claims.

I claim:

1. A braiding machine comprising a carrier having means for supporting a plurality of bobbins for supplying individual strands, and tensioning and guiding means on said carrier for regulating the tension of the group of strands supplied by said bobbins, said tensioning and guiding means comprising a single eye for guiding the group of strands collectively, means for simultaneously applying tension to all the bobbins, and means controlled by the tension of a bight of a strand for automatically relieving excessive tension upon at least one of the strands.

55 2. A braiding machine comprising a carrier having means for supporting a plurality of bobbins for supplying individual strands, and tensioning and guiding means on said carrier for regulating the tension of the group of strands supplied by said bobbins, said tensioning and guiding means comprising a single eye for guiding the group of strands collectively, means for simultaneously applying tension to all the bobbins, and means controlled by the tension of a bight of a strand for automatically relieving excessive tension on that strand.

60 3. A braiding machine comprising a carrier having means for supporting a plurality of bobbins for supplying individual strands, and tensioning and guiding means on said carrier for regulating the tension of the group of strands supplied by said bobbins, said tensioning and guiding means comprising a single spindle for rotatably supporting in side by side relation a plurality of bobbins, friction means adapted to restrain rotation of said bobbins, means for an-

choring said friction means against rotation with said bobbins, and means for releasing the friction means from said last-named means when the tension of a strand becomes excessive.

4. A braiding machine comprising a carrier having means for supporting a plurality of bobbins for supplying individual strands, and tensioning and guiding means on said carrier for regulating the tension of the group of strands supplied by said bobbins, said tensioning and 10 guiding means comprising a single spindle for rotatably supporting in side by side relation a plurality of bobbins, brake means engaging a bobbin to tension the strand therefrom, and means controlled by the tension of a bight of said 15 strand to automatically release the bobbins from

said brake means when the tension of said strand becomes excessive.

5. In a braiding machine a carrier comprising a plurality of bobbins each delivering a strand, 5 means for guiding the strands together into a group thereof, and means mounting said bobbins for rotation individually and for rotation induced from one bobbin to another through friction therebetween.

6. In a machine for grouping strands from individual sources a plurality of bobbins, means mounting said bobbins for rotation individually and for rotation induced from one bobbin to another through friction therebetween.

EDWARD A. DAVIS.
